W. H. BANKS

SAFETY HIGHWAY APPROACH TO RAILWAY CROSSINGS

Filed Nov. 15. 1922

FIG. 1.

FIG. 2.

INVENTOR:

William H. Banks

by MacLeod, Calfee, Copeland & die

Atty's-

UNITED STATES PATENT OFFICE.

WILLIAM H. BANKS, OF WINTHROP, MASSACHUSETTS.

SAFETY HIGHWAY APPROACH TO RAILWAY CROSSINGS.

Application filed November 15, 1922. Serial No. 601,172.

To all whom it may concern:

Be it known that I, WILLIAM H. BANKS, a citizen of the United States, residing at Winthrop, county of Suffolk, State of Massachusetts, have invented a certain new and useful Improvement in Safety Highway Approaches to Railway Crossings, of which the following is a specification, reference being had therein to the accompanying drawings.

It is well known that many of the accidents to automobilists at railway crossings is due to the fact that the driver of the car fails to slow down properly as he approaches the crossing, and that he discovers the danger from an approaching train too late to stop before driving onto the tracks in front of the train. If the driver is compelled to come down to relatively slow speed at some distance before he reaches the railroad, he will then have sufficient time to come to a dead stop if he discovers the danger from an approaching train, even only a short distance before he reaches the track. The object of the present invention is to provide such a construction in the approach to the railroad that the driver will be forced to check his speed in some degree, at least, at some distance before he reaches the railroad, if he has been driving fast, so that he will thereby have his car under such control that he can come to a dead stop after reaching the safety device before actually reaching the tracks.

The invention will be fully understood from the following description when taken in connection with the accompanying drawings, and the novel features thereof will be pointed out and clearly defined in the claims at the close of this specification.

In the drawings, Fig. 1 is a plan view of a portion of a railroad and of a highway crossing the tracks, provided with a safety approach in the highway on each side of the railroad.

Fig. 2 is a vertical section on line 2—2 of Fig. 1.

Referring now to the drawings, 1—1 represent two parallel railroad tracks, 2 the travel portion of a highway, and 3 the crossing for the highway over the tracks.

In the middle of the highway a short distance back from the railroad crossing, there is erected a guard 4 of curved outline, preferably circular. This guard may be of any

suitable construction but is preferably made of cement or stone. The road is widened out and branches to pass around this circular guard, the two branch portions 5—5 coming together to form a single driveway after they pass the guard.

These two branch portions are bordered by walls 6—6 so that the passage around the guard is bordered by a wall on each side.

Preferably the two side walls are extended to form diverging portions 7—7 at the ends toward the crossing, these diverging portions being curved outwardly so as to avoid any angular corners.

At the entrance end, that is at the end farther away from the railroad crossing before the road branches, the said side walls will be extended backward, diverging backwardly on the curve, as shown at 8—8, so as to avoid sharp angles in the driveway at that end. It will thus be seen that there is a sinuous approach to the crossing, so that if a person is driving fast before reaching the point where the road branches, he will practically be forced to check his speed if he is driving at high speed or at least it will be a caution to him that he should check his speed.

Preferably the circular guard 4 should be of sufficient diameter so that the vehicle will have to make a very substantial turn out of a straight course to go around it. Preferably the guard is of sufficient height so that it will be impossible for a vehicle to drive over it.

Preferably the center guard 4 and outside guards 6—6 as well as the end extensions thereof have a sloping or beveled face 9 so as to furnish a little more clearance for the wheels and less danger of accident if the car drives close to the guard.

If a person is driving a vehicle at great speed, as he approaches the railway crossing, he will be obliged to slow down as he enters the circle, and thus bring his car to a slow enough speed, so that if, after he enters the circle, he sees an approaching train near the crossing, he will have ample time to bring his car to a full stop before reaching the railroad tracks. If he finds that he cannot easily come to a full stop, he can easily swing around the circle to the other side of the center guard 4, and head away from the railroad, and will then easily be able to come to a stop before he makes the complete circle,

2
or, if he wishes, he can continue driving around in a circular path without stopping his car at all, and then be in position to drive across the track when the train has passed.

Preferably there are removable sections 10, 11 to the wall of the inner guard at the ends of the branch passages to allow a little more free entrance for an unusually large 10 vehicle or bulky load such, for instance, as in the moving of a building or long, heavy pieces of timber.

Preferably the outer removable sections 10 are formed as resilient bumpers to reduce 15 the shock in the event that the vehicle should not make the turn quick enough and should run into the middle guard 4 after it enters the branch portion of the road. These resilient sections may be made of bars or rails 20 of spring metal which are held in place by slotted supports 12. These bars are curved to conform to the curvature of the wall and will yield to the impact of a car. They may be removed by sliding them through the 25 slotted supports.

What I claim is:—

1. A safety highway approach to a railway crossing comprising an enclosed area of 30 curved contour in the middle of the highway somewhat back from the crossing and surrounded by a guard, the highway being divided into two branches to pass around said area, said branches merging together on the side toward the crossing, the guard having movable sections adjacent the beginning 35 of the branching of the highway and adjacent the merger of the two branches, said movable sections being adapted to be opened for emergency use.

40 2. A safety highway approach to a railway crossing comprising an enclosed area of

curved contour in the middle of the highway somewhat back from the crossing and surrounded by a guard, the highway being divided into two branches to pass around 45 said area, said branches merging together on the side toward the crossing, the guard having movable sections adjacent the beginning 50 of the branching of the highway and adjacent the merger of the two branches, said movable sections being adapted to be opened for emergency use, the movable section adjacent the entrance to the branched portion of the driveway being resilient to 55 form a yielding bumper.

3. A safety highway approach to a railway crossing consisting of a driveway divided into two substantially semi-circular branches at a short distance back from the crossing, the two branches being merged together again nearer the crossing, an enclosed area surrounded by the two branches, a guard surrounding said area and forming an inside boundary for the two branches, 60 said guard having movable sections at the point where the driveway divides into the branches and adjacent the point where the two branches merge together, and guards bordering the outer sides of the two branches. 65

4. A safety approach to a railway crossing consisting of a driveway which divides into two curved branches at a short distance before it reaches the crossing, said two branches merging together, again at a point nearer the crossing, an enclosed area between said two branches, and a guard surrounding said area having a resilient bumper section adjacent the point where the driveway divides into two branches. 70 75

In testimony whereof I affix my signature.

WILLIAM H. BANKS.
